(57) **CLAIM**

The ornamental design for a nerve cutting device as shown
and described.

DESCRIPTION

FIG. 1 is a perspective view of a nerve cutting device
showing our new design;

FIG. 2 is a first side view thereof;

FIG. 3 is a second side view thereof;

FIG. 4 is a front view thereof;

FIG. 5 is rear view thereof;

FIG. 6 is a top view thereof;

FIG. 7 is a bottom view thereof; and

FIG. 8 is a perspective view of a second embodiment of a
nerve cutting device showing our new design;

FIG. 9 is a first side view thereof;

FIG. 10 is a second side view thereof;

FIG. 11 is a front view thereof;

FIG. 12 is rear view thereof;

FIG. 13 is a top view thereof; and,

FIG. 14 is a bottom view thereof.

The broken lines in the figures illustrate portions of the nerve
cutting device that form no part of the claimed design.

1 Claim, 8 Drawing Sheets
